THOMAS SIMMONS, OF NEW YORK, N. Y.

Letters Patent No. 67,812, dated August 13, 1867.

IMPROVEMENT IN STEAM-PUMPS.

The Schedule referred to in these Letters Patent and making part of the same.

TO ALL WHOM IT MAY CONCERN:

Be it known that I, THOMAS SIMMONS, of New York, in the county of New York, and in the State of New York, have invented certain new and useful Improvements in "Vacuum Ship-Pumps;" and do hereby declare that the following is a full, clear, and exact description thereof; reference being had to the accompanying drawings, making a part of this specification.

My invention consists, in part, of a hollow vessel of metal or any other suitable substance, and of any given dimensions, or any conceivable form, as circumstances and location may permit; but a cylindrical form is preferred on account of strength and convenience. Therefore, in—

Figure I, A represents a hollow vessel, of a cylindrical form, made air-tight and lying horizontally on and supported by a bed or trough, B, and fastened to the trough by means of screw-bolts through flanges projecting from the sides of cylinder, and resting on the edges of trough B and is thus held in position. Through the centre of cylinder A runs a perforated plate, a, from end to end, filling the entire width of the cylinder, (thickness of plate boiler iron.) At one end of cylinder A is a box, C, which contains a check or flap-valve, E. Box C is so constructed as to be open on top side, and with plate, yoke, lever, and screw *s t w*, so as to close quickly and easily. This opening on the upper side is so as to remove any substance that might pass into the valve and obstruct its action. The other opening is to pass water or any other liquid into cylinder A. By means of a corresponding hole in the end inside of box C is a valve-fall and valve E. The valve-fall is made of a square plate of metal with square hole through the centre, and fitted in box C at any angle, so that the water in passing through will work off any substance which may collect there on the valve-faces, and thus interfere with its action or the working of the valves. The valve E is made of a flat piece of metal, or suitable substance faced with rubber or any elastic substance, then fastened in such manner as to rise and fall by means of a hinge formed by the rubber, so as to close the square hole through valve-face perfectly tight. The rubber is used so that sand or any small hard substance would indent itself into it and not prevent it working or acting. On the lower side of box C is a nipple, F, or a screw-connection, for the purpose of attaching a pipe or hose through which the water is to be drawn. Box C is arranged with flanges so that it can be bolted against the end of cylinder A. On the top of cylinder A is a nipple, G, for the purpose of making a steam-connection to admit steam, and is worked by hand or otherwise, by means of an ordinary cock or valve. On the opposite end of cylinder A, to which box C is fastened, is valve-seat and chamber H, in which works valve I. Seat and chamber H is a round cylinder with flange at one end to fasten with screw and bolts to cylinder A, and the other end is turned or forced off true and the cylinder part bored out. In this the stem, or flanges, or wings of valve play as a guide to the valve, while the face of the valve is made to correspond to that of the seat and face, with rubber or other elastic substance for the same purpose that the other valve is used for in box C. This valve I is worked by means of a lever, J, which is to be worked by hand or otherwise, and stands in an upright position, and is supported on shaft K. This is worked and fastened by means of boxes, journals, and collars on trough B. By the action of the lever on valve I it may be forced shut or open, as desired. The trough B is made of wood or metal, as desired, and acts in the double capacity of a bed-plate and for the conducting of the water or liquid matter discharged and delivered by the pump. It is made of two sides, one end and bottom, with one end hollowed out so as to fit the circle of cylinder A, with corresponding circular bearer at the end where cylinder rests.

Now, having described my invention by detail, I will proceed to show its working operation: First, steam is admitted at connection G into cylinder A. When the air in A has been displaced by steam it is then shut off, when a vacuum is formed in A, so that water shall meet with no resisting pressure when being forced up through a pipe or hose attached to screw-connection F, into box C through valve E, and is thrown upon perforated plate a until cylinder A is filled. Steam is then admitted into vessel A through G, and forces open delivery-valve I, and the contents are discharged into trough B and conducted off with the water discharged. The valve I is then forced and held shut by means of lever J, and the operation repeated.

Now, having thus fully described my invention, and the mode of working it, what I claim and desire to secure by Letters Patent, is—

1. The arrangement of cylinder A, perforated plate a, and box C, substantially as herein set forth.
2. The arrangement of the cylinder A, steam inlet G, chamber H, valve I, and lever J, in the manner and for the purposes set forth.

In testimony that I claim the foregoing I have hereunto set my hand this 18th day of April, 1867.

THOMAS SIMMONS.
